UNITED STATES PATENT OFFICE.

ERUCHSHAW BYRAMJI DAROWALLA, OF BOMBAY, INDIA.

PADLOCK.

1,194,720.

Specification of Letters Patent. Patented Aug. 15, 1916.

Application filed January 4, 1916. Serial No. 70,202.

To all whom it may concern:

Be it known that I, ERUCHSHAW BYRAMJI DAROWALLA, a subject of the Emperor of India, residing at Bombay, India, have invented certain new and useful Improvements in Padlocks, of which the following is a specification.

This invention relates to improvements in padlocks.

It comprises a key with two bits on the same side of the stem operating two separate bolts one of which locks the other. The shackle is split, each half opening from the opposite side of the case, while the padlock is divided into two compartments by a partition, a bolt working in each. The key moves clockwise in opening it and engages the bolts in different portions of a revolution, thus insuring extra security, but as the two movements commence at right angles to each other one of them has to be reversed in order to give the bolts their proper direction.

Referring to the annexed sheet of drawings, Figure 1 shows the padlock with the cover and partition removed. Fig. 2 is a similar view with the partition in place. Fig. 3 is a cross section through the center of the padlock. Fig. 4 shows the key with two bits in line and so spaced as to enter their respective compartments in the padlock, and Fig. 5 is an elevation of one of the tumblers.

The shackle *c* is split as shown in Fig. 3 each half being hinged at one side of the case and entering a recess in a boss at the other side. The two halves are locked in this position by the mechanism within.

In Fig. 1 the bolt *f* is pivoted at *g* and enters a recess *r*; the other end of *g* is pivoted at *h* to the key bar *s* working in guides *i*, *j*, and *k*, *l*. It is operated by the key working clockwise in the hole *n*. The second bolt *t* is seen in Fig. 2 lying against the partition *b* (Fig. 3) and between the guides *w* and *v*. Fig. 1 shows the bolt *f* lying against the bottom of the case, upon the fulcrum *g* and is hinged to the key bar *s* which works between the guides *i*, *j*, and *k*, *l*. The end of the key enters the hole *n* and its course is shown by the circular dotted line around it. Two projections *y* on the key bar *s* engage with a single projection *x* passing from the bolt *t* (Figs. 2 and 3) through the partition *b*. The bolt *t* lies

upon the partition *b* and occupies the outer compartment below the cover *t*¹ and engages at the point *q* with the right hand boss *d*¹ and it moves within guides *v* and *w*. For clearness the tumblers are not shown in 60 these figures, but are shown separately in Fig. 5.

The locking of the two bolts takes place as follows:—The projection *x* on the under-side of the bolt *t* passes through the partition and enters between two projections *y* (Fig. 1) upon the key bar *s*. The drawing shows the bolts locked and to open them the key would first move the bolt *t* downward releasing the bolt from the boss *d*¹ and carrying the projection *x* below from the projections *y* on the key bar *s* thus freeing it. The key continues its movement pushing the key bar to the left along with the lower end of the lever bolt *f* causing the end *r* 75 to be released from the boss *d*. The shackle may then be opened.

The lock is furnished with the usual tumblers which for the sake of clearness are represented in Fig. 5; they are pivoted upon 80 the pin *m*¹ in Fig. 1 and on the pin *u* in Fig. 2.

What I claim as my invention and desire to secure by Letters Patent is:—

1. In a padlock, the combination of a 85 shackle divided longitudinally into two sections, and rotatable bosses on opposite sides of the padlock to which each of the shackle sections respectively are permanently connected at one end and with which the other 90 end of each shackle section respectively engages when in the closed position.

2. In a padlock, the combination of a shackle divided longitudinally into two sections, rotatable bosses on opposite sides of 95 the padlock to which each of the shackle sections respectively are permanently connected at one end and with which the other end of each shackle section respectively engages when in the closed position, a bolt 100 located within the padlock and pivoted intermediate its ends and adapted to engage one of said bosses with one end, and a key bar connected to the other end of the bolt for the purpose described.

3. In a padlock, the combination of a shackle divided longitudinally into two sections, rotatable bosses on opposite sides of the padlock to which each of the shackle sections respectively are permanently connected at 110

one end and with which the other end of each shackle section respectively engages when in the closed position, a bolt located within the padlock and pivoted intermediate its ends and adapted to engage one of said bosses with one end, a key bar connected to the other end of the bolt, and a second bolt adapted to engage the other of said bosses and to be moved longitudinally

out of engagement by a key for the purpose 13 described.

In testimony whereof I have signed my name to this specification in the presence of two subscribing witnesses.

ERUCHSHAW BYRAMJI DAROOWALLA.
